UNITED STATES PATENT OFFICE.

JAMES H. MONTGOMERY, OF BUTTE, MONTANA.

GREASE-DISPENSING DEVICE.

1,338,519.

Specification of Letters Patent. Patented Apr. 27, 1920.

Application filed September 29, 1916. Serial No. 122,862.

To all whom it may concern:

Be it known that I, JAMES H. MONTGOMERY, a citizen of the United States, residing at Butte, in the county of Silverbow, State of Montana, have invented certain new and useful Improvements in Grease-Dispensing Devices, of which the following is a description, reference being had to the accompanying drawing and to the figures of reference marked thereon.

The invention relates to new and useful improvements in grease dispensing devices and more particularly to a device whereby grease received in commercial receptacles or barrels may be dispensed directly from the receptacle or barrel in which it is received.

An object of the invention is to provide a grease dispensing device of the above character which is so constructed that the entire contents of the receptacle or barrel may be dispensed through said dispensing device.

A further object of the invention is to provide a device of the above character having a dispensing pump and an intermediate receptacle which is adapted to receive the barrel or receptacle in which the grease is shipped in inverted position so that the grease may be fed by its own weight into this intermediate receptacle and from the intermediate receptacle to the pump.

A still further object of the invention is to provide a grease dispensing device having a pump and a reciprocating piston for dispensing the grease with a vent opening for the pump which is so disposed as to permit the air to escape from the pump so that the grease may enter the same by gravity.

These and other objects will in part be obvious and will in part be hereinafter more fully disclosed.

In the drawings which show by way of illustration one embodiment of the invention:

Figure 1 is a vertical sectional view through a dispensing device embodying my improvements.

Fig. 2 is a sectional view on the line 2—2 of Fig. 1.

Fig. 3 is a sectional view on the line 3—3 of Fig. 1.

The grease dispensing device consists of a support mounted on suitable rollers and embodied in this supporting device is a pump having means for forcibly expelling the contents of the receptacle. This pump may be in the form of a reciprocating piston pump or in the form of a screw pump. The support also carries a receptacle which receives the grease from the barrel or receptacle in which it is shipped and delivers the same to the pump. This receptacle is preferably tapered so as to provide a wide open upper section onto which the receptacle or barrel is inverted after the entire end has been taken out of the barrel so that the grease in the barrel will pass by gravity down into the intermediate receptacle and thence into the pump. In a reciprocating pump when the piston is brought back air is liable to accumulate in front of the piston and prevent the grease from passing by gravity into the pump. In order to permit the free flow of the grease into the pump I have provided said pump with a vent hole which is uncovered when the piston is withdrawn so that any air in advance of the piston may be forced out of the pump by the grease as it is forced by its own weight into the pump. This vent hole is, of course, closed when the piston moves forward to expel the grease in the pump.

Referring more in detail to the drawings my improved grease dispensing device consists of a support 1 which is mounted on wheels 2—2 and a roller 3 attached to a bracket at the forward end of the support. These wheels and the roller facilitate the movement of the dispensing apparatus from one point to another. Formed as a part of the support or extending upwardly therefrom is a receptacle 4. This receptacle has tapered side walls 5 and 6 which are joined to the pump casing 7 at their lower edges. Said receptacle 4 also has a rear tapered wall 8. The side walls of the receptacle 4 are substantially vertical at the upper part of the receptacle thus forming a wide open mouth. The grease is shipped in receptacles or barrels, one of which is indicated at B in the drawings. This receptacle or barrel is provided with a suitable bottom 9.

and is adapted to be inverted and have its upper end extending within the receptacle 4 on which it rests. After the barrel or receptacle has been inverted on the dispensing device it may be held thereon by a metal strip 10 which is attached to the device at its lower end and which is adapted to be bent over as at 11 so as to engage the barrel or receptacle B.

10 The pump casing 7 is provided with an inner section 12 in which a piston 13 is reciprocated by means of a piston rod 14. The piston rod 14 slides in a bracket 15 and is moved back and forth by a hand lever 16 which in turn is pivoted to a bracket 17 detachably connected to the grease dispensing device. This inner section 12 extends from end to end of the pump and is provided with an opening 18 which is adapted to register with an opening 19 in the side wall of the pump, when said inner section is in the position shown in Figs. 1 and 2 of the drawings. The piston rod 14 has a spiral groove 20 formed therein. The inner section 12 carries 25 a lug which engages the groove 20 so that when the piston rod is moved forward it will rotate the inner section 12, thus closing the opening 19.

30 The pump casing is formed with an opening 21 connected with a pipe 22 leading to the atmosphere. The inner casing 12 has an opening 23 which registers with the opening 21 when the parts are in the position shown in Fig. 1 (see Fig. 3). The 35 pump casing 7 has a delivering nozzle 24 to which a flexible pipe 25 may be attached.

In the operation of my device the grease is received in commercial barrels or receptacles made for the purpose. The upper 40 end of the barrel is removed and the grease dispensing device is inverted and attached to the open end of the barrel by slipping the vertical portion of the intermediate receptacle over the top of the barrel or receptacle. These parts are then connected by the vertical strip 10 after which the 45 whole device with the barrel is turned over to the position shown in Fig. 1. This allows the entire contents of the barrel to 50 slide down into the intermediate receptacle 4 and fill the same. The pump is usually left with the piston 13 forward and this closes the opening in the side wall of the pump chamber. The operator withdraws 55 the piston which turns the inner casing and opens the pump chamber to the intermediate receptacle 4. The pump chamber is also opened to the atmosphere. The grease in the intermediate chamber flows by gravity 60 down into the pump chamber. When the piston is moved forward the grease in the pump chamber will be forced out through the delivering nozzle and the flexible pipe 25.

65 From the above description it will be

apparent that the grease will flow from the barrel or receptacle in which it is shipped into the intermediate receptacle and thence into the pump and finally the barrel or receptacle in which the grease is shipped will 70 be emptied. When the barrel is emptied it will be removed and another barrel inverted on the dispensing device in the manner above described. By my improved dispensing device the entire contents of the 75 barrel may be emptied. In order that the sides of the barrel may be scraped I have provided a follower 26 which is secured to the bottom of the barrel by small bolts 27. After the contents of the barrel have been 80 completely dispensed these bolts may be released and the follower 26 will drop of its own weight thus scraping the sides of the barrel. It is obvious that the barrel may be provided with a suitable vent open- 85 ing, if desired.

In the construction shown in Fig. 1 the pump casing is of a predetermined size and therefore the amount of grease dispensed may be determined by the number of re- 90 ciprocations of the piston.

It is obvious that minor changes in the details of the construction may be made without departing from the spirit of the invention as set forth in the appended 95 claims.

Having thus fully described my invention what I claim and desire to secure by Letters Patent is:—

1. A grease dispensing device including 100 in combination a receptacle having vertical walls at its upper end and tapering side walls at its lower end, a horizontal stationary cylindrical member communicating with the opening between the lower ends 105 of the tapering walls, a rotary cylinder within the stationary cylinder and having an opening corresponding with the opening in the stationary cylinder, a piston in the rotary cylinder, a piston rod, means carried 110 by the piston rod for rotating the cylinder for preventing grease from entering the cylinder in rear of the piston on the forward movement of the piston.

2. In an apparatus of the character described, the combination with a receptacle including a support secured to the receptacle, a cylinder carried by the support and in communication with the receptacle, a piston for forcing the grease from the cylinder, means operated by the forward movement of the piston for closing the communication between the cylinder and the receptacle during the time the piston is forcing the grease from the cylinder.

3. In an apparatus of the character described, the combination of a receptacle provided with a mouth portion adapted to receive and hold thereon in inverted position a receptacle containing grease in bulk,

said receptacle having tapering sides, a cylindrical casing having an opening arranged at the junction of said tapering sides and provided with a grease nozzle, 5 an apertured sleeve valve movable in said casing to open and close said casing opening, and means in said casing to force said grease therein out through said nozzle, said

means controlling the movement of said sleeve valve.

In testimony whereof, I affix my signature in the presence of two witnesses.

JAMES H. MONTGOMERY.
